UNITED STATES PATENT OFFICE.

WILLIAM D. GHERKY, OF PHILADELPHIA, PENNSYLVANIA.

MONORAIL-GRINDING MACHINE.

1,095,964.

Specification of Letters Patent.

Patented May 5, 1914.

Application filed January 18, 1913. Serial No. 742,936.

To all whom it may concern:

Be it known that I, WILLIAM D. GHERKY, a citizen of the United States, residing at Philadelphia, in the county of Philadelphia and State of Pennsylvania, have invented 5 certain new and useful Improvements in Monorail-Grinding Machines, of which the following is a specification, reference being had therein to the accompanying drawing.

10 This invention relates to machines designed for grinding track rails especially at the joints of adjacent rail sections, as well as frogs, crossings, switches and the like, to remove or modify the shape of depressions 15 that are worn therein in the course of time by the passage of the train wheels thereover. It is also useful for deepening or widening the flange-ways of rails or spinal work in tracks, made desirable by the wearing down 20 of the head of the rail or by the use of larger flanges on the car wheels.

The principal object of the invention is the provision of a grinding machine of that 25 type having a rotary or equivalent grinding element that travels along the rail head or the tram to grind a comparatively even surface thereon where depressions, corrugations or the like, may occur, or to deepen or enlarge the flange-ways, where desired, the 30 grinding element being guided by a frame or equivalent support so shaped as to give the proper slope to the rail head or the tram merely by the movement of the grinding element longitudinally of the frame or support. 35

In carrying out the invention, the grinding element or wheel is mounted in the carriage which is slidably mounted in an approximately horizontal frame that sags uniformly 40 between its ends on a radius of great magnitude, the lowest part of the frame being at the middle; or the frame may be shaped to cause the grinding to follow a flat sinusoidal curve which becomes horizontal 45 at each end and therefore tangent to the surface of the rail. The frame is set up on the track to be ground with the lowest part of the frame directly over the point where the depression is worn by the passage of the 50 train wheels. According to the depth of the depression, the frame is adjusted vertically to bring the grinding wheel into contact with the rail at a point to one side of the depression. The wheel is then driven at a 55 high speed and simultaneously the carriage is moved slowly in the guide frame to grind

the rail. The movement of the carriage is continued in one direction until the grinding element or wheel leaves the rail. By this operation, the rail is given a curvature corresponding to the curvature of the guiding frame or support on which the grinding wheel travels, making a hollow so shallow and of such width and gradient that the train wheels can pass over the defect without perceptible shock or jar. 60

With such and other objects in view, as will appear as the description proceeds, the invention comprises the various novel features of construction and arrangement of 70 parts which will be more fully described hereinafter and set forth with particularity in the claims appended hereto.

In the accompanying drawings, which illustrate one embodiment of the invention, 75 Figure 1 is a side view of the machine. Fig. 2 is a plan view thereof. Fig. 3 is an enlarged transverse section taken adjacent the center of the machine. Fig. 4 is an end view of the machine. Fig. 5 is a perspective view 80 of one of the shoes or foot plates which rest on the track rail to support the machine. Figs. 6 and 7 are diagrammatic views to illustrate the use of the machine.

Similar reference characters are employed 85 to designate corresponding parts throughout the views.

Referring first to Figs. 6 and 7, the purposes of the machine will be first explained. The track rails 1 and 2 are shown with their 90 adjacent ends worn away at 3, forming a depression which it is the object of the grinding machine to remove, or rather to correct in such a manner as to prevent shocks and jars as the train wheel passes over the 95 joint. The depression 3 is in fact made many times wider by imparting a gradual slope to the head of the rail sections, the slope being, for instance, on the dotted line 4, Fig. 6, or 5, Fig. 7. The length of the 100 slope will depend upon the depth of the depression at the joint. With a deeper depression than that shown in Fig. 6, as for instance, a depression represented by the dotted lines 6, the head would be ground to 105 slope as indicated by the dotted line 7. In grinding the head for the shallow depression 3, the grinding wheel 8 will be set to begin grinding in the position shown in full lines, and as the wheel is rotated, it is moved gradually toward the right, Fig. 6, so as to produce the sloping surface 4, Fig. 6, Fig. 7, on

the rail 2. The movement of the wheel to the right is continued until the head of the rail 1 is given a corresponding sloping surface, such as 9, Fig. 6. In case of a deeper 5 depression, the initial position of the wheel will be more remote from the joint, as at 8^a, Fig. 6. In order to obtain this proper adjustment of the wheel, it is merely necessary to adjust the supporting frame for the wheel 10 toward or from the rail head, as will be more fully described hereinafter.

The grinding machine comprises a frame A which, in the present instance, is shown as a rectangular structure formed of two 15 side channel bars 10 and 11, which are connected together by end pieces 12, the channel bars being so arranged that their hollow sides are opposed to each other so that the upper and lower webs 13 and 14 of each 20 channel bar form a guideway or track for the carriage B which contains the grinding wheel C. The channel bars curve downwardly from their ends toward the center on a radius of great magnitude. In other 25 words, the frame A is constructed with a very shallow sag of uniform gradation from each end to the center.

The frame A is supported on the end legs 15 and a middle leg 16 disposed to one side 30 of the frame A, so that the latter has a three-point support. The end pieces 12 have upwardly-extending brackets 17 formed with internally threaded bosses 18 into which the upper ends of the standards 15 are threaded. 35 Also on the end pieces 12 are guide brackets 19 through which the standards 15 extend and are free to rotate. The upper extremities 20 of the standards are square to receive a crank or equivalent means so as to rotate 40 the standards to raise or lower the frame A. The lower end of each standard is formed with a foot plate 21 which is flat and rests on the upper surface of a flat shoe or plate 22, the latter having a rib 23 to enter the 45 groove 24, Figs. 3 and 4, of the track rail. The shoes 22 are connected with the guide brackets 19 by suitable connecting elements or bolts 25 which are fastened in the shoes 22 and pass loosely through the guide brackets 50 19. To insure simultaneous rotation of the end standards 15 so that both ends of the frame A will be raised or lowered simultaneously, each standard has a sprocket wheel 26 and a sprocket chain 27 disposed under 55 the frame A engaged with the sprocket wheels and operatively connects the standards together, so that rotation of one standard will impart rotation to the other.

The standard 16 is constructed like the 60 standards 15 and is threaded in the outer end 28 of an arm 29, which arm is pivoted at 30 to a sector-shaped bracket 31 fastened to the side of the frame A at the middle thereof, said bracket having an arcuate slot 32 con- 65 centric with the pivot 30, and through the

arm passes a bolt 33 for rigidly clamping the arm to the bracket 31. By means of this slot and bolt connection, the arm 30 can be adjusted to any desired position for properly placing the supporting standard 16. By 70 turning the standard 16, the supporting frame A can be adjusted to incline the grinding element C so as to produce any desired angularity of cutting on the rail.

The carriage B is a rectangular frame 75 which is of such size as to set in between the channel bars 10 and 11 of the main frame A, a portion of the carriage frame extending above the main frame for the passage of an arbor 34 on which the grinding 80 wheel C is mounted, the arbor being journaled in bearings 35 in the carriage frame. One end of the arbor is connected to a driving shaft 36 which is of the usual flexible type and driven from a portable motor and 85 the opposite end of the shaft has an extension 37 on which is a loose handle 38 by which the workman moves the carriage and grinding wheel longitudinally of the main frame A. Extending from opposite sides of 90 the carriage B are means for slidably engaging in the guideways formed by the flanges 13 and 14 of the channel bars 10 and 11. In the present instance, these means 95 are sets of rollers 39 and 40 that engage, respectively, the upper and lower flanges 13 and 14, there being two sets of such rollers at each side of the carriage frame so as to give greater stability thereto in the main frame.

In using the machine, the same is set up on the track to be ground as shown in the drawings. The curved main frame A or guide for the carriage B is then adjusted vertically on the standards 15 and 16 so 105 as to bring the grinding wheel into proper relation to the head of the rail, according to the depth of the depression at the joint between the rail sections to accomplish the results explained in connection with Figs. 6 110 and 7. In setting up the machine, the lowest part or middle of the curved carriage guide A is directly over the joint to be ground. After the machine is properly adjusted, the power is turned on to rotate the grinding 115 wheel C and thereupon the carriage is moved longitudinally of the guide to dress the head of the rail in the manner hereinbefore explained.

From the foregoing description, taken in 120 connection with the accompanying drawings, the advantages of the construction and of the method of operation will be readily apparent to those skilled in the art to which the invention appertains, and while I have 125 described the principle of operation of the invention, together with the device which I now consider to be the best embodiment thereof, I desire to have it understood that the device shown is merely illustrative, and 130

vided with a gear wheel 84 which is driven by means of an interposed idle gear pinion 85 which meshes with the gear wheel 82 on the hand shaft and is pivotally mounted on 5 the underside of the table.

When the machine is to be driven by power the idle gear wheel or pinion 85 may be engaged by a gear wheel or pinion 86 which is mounted on the upper end of an upright 10 motor shaft 87. Any suitable motor may be employed, that shown in the drawings being an electric motor 88 which is mounted on a vertically adjustable shelf 89 so that this motor may be raised or lowered for 15 either engaging its driving gear pinion with or disengaging the same from the idle gear wheel. The adjustment for this shelf which is shown in the drawings comprises a vertical stem or rod 90 depending from the 20 underside of the shelf and adjustably secured by means of a set screw 91 in a bracket 92 mounted on the lower part of the standard.

The bearing 80 of the hand shaft is preferably made separate from the table and secured to the latter by means of screws 93 passing through lugs 94 on this bearing and into the table, whereby this bearing when worn may be renewed without the use of 30 bushings in the same manner as the bearings of the printing wheel shaft and of the shaft which carries the front feed belt roller and stacker cam arms.

As a whole this mail marking machine is 35 of very simple construction, it can be produced at comparatively low cost the same has no delicate parts which are liable to get out of order and it permits of effecting the cancellation or marking of mail matter at 40 a high rate of speed without liability of feeding more than one letter at a time and without soiling the letters with ink, thereby meeting all the standard postal requirements at the present time.

45 I claim as my invention:

1. A mail marking machine comprising means for feeding letters, and a printing device comprising a printing wheel arranged on one side of the letter path, an eccentric 50 journaled in a bearing, a pivot pin arranged on the upper end of said eccentric and having its axis on one side of the axis of the eccentric, an impression roller arranged on the opposite side of the letter path trans- 55 versely in line with the printing wheel and journaled on said pivot pin, a trip finger arranged on the upper end of said pivot pin and adapted to project across the letter path so as to be engaged by the front edge of the 60 letters, a spring surrounding the lower end of the eccentric and connected at its opposite ends with said eccentric and said bearing, and a stop arranged at the upper end of the

eccentric and adapted to engage with a stop on the upper end of said bearing for limiting the turning of said eccentric under the action of said spring. 65

2. A mail marking machine comprising means for feeding letters, and a printing device comprising a printing wheel arranged 70 on one side of the letter path, an eccentric journaled in a bearing, a pivot pin arranged on the upper end of said eccentric and having its axis on one side of the axis of the eccentric, an impression roller arranged on the 75 opposite side of the letter path transversely in line with the printing wheel and journaled on said pivot pin, a trip finger arranged on the upper end of said pivot pin and adapted to project across the letter path 80 so as to be engaged by the front edge of the letters, a spring surrounding the lower end of the eccentric and connected at its opposite ends with said eccentric and said bearing, a stop arranged at the upper end of the 85 eccentric and adapted to engage with a stop on the upper end of said bearing for limiting the turning of said eccentric under the action of said spring, a rock arm carrying 90 said bearing, a spring operating to swing said arm toward the letter path, and a stop for limiting the movement of said arm under the action of said last mentioned spring.

3. A mail marking machine comprising a separator, a letter feeding belt moving 95 with its face past said separator, said belt and separator forming a throat through which the letters are moved successively by said belt, a belt support for supporting the back of said belt opposite said separator, a 100 printing couple to which the letters are moved by said feeding belt and which has a printing wheel and an impression roller arranged on opposite sides of the letter path, the distance from said throat to the printing 105 point between said wheel and roller being less than the diameter of said printing wheel, a time stop arranged opposite the face of said belt in close proximity to the outlet of said throat between said separator 110 and belt and having two stop fingers which in the operative position of the time stop project across the letter path adjacent to the upper and lower edges of the feeding belt, means for moving said time stop yielding toward the face of the belt, and means for periodically moving said time stop away from said belt in harmony with said printing wheel. 115

Witness my hand this 17th day of March, 120 1913.
